[57] CLAIM

The ornamental design for a hat mounted golf range finder, as shown and described.

DESCRIPTION

FIG. 1 is a front perspective view of a hat mounted golf range finder showing our new design;
FIG. 2 is a front perspective view thereof, the visor is drawn broken away for clarity of illustration;
FIG. 3 is a front elevational view in an alternate position;
FIG. 4 is a rear elevational view thereof;
FIG. 5 is a right side elevational view thereof;
FIG. 6 is a left side elevational view thereof;
FIG. 7 is a top plan view thereof; and,
FIG. 8 is a bottom plan view thereof.

The broken line showing of the hat is for illustrative purposes only and forms no part of the claimed design.
